UNITED STATES PATENT OFFICE.

JOHN T. QUIGLEY, OF BOSTON, MASSACHUSETTS, ASSIGNOR TO COSTMETER COMPANY, OF BOSTON, MASSACHUSETTS, A CORPORATION OF MASSACHUSETTS.

FILING AND INDEXING EQUIPMENT.

Application filed December 14, 1918. Serial No. 266,743.

To all whom it may concern:

Be it known that I, JOHN T. QUIGLEY, a citizen of the United States, and a resident of Boston, county of Suffolk, and State of Massachusetts, have invented an Improvement in Filing and Indexing Equipments, of which the following description, in connection with the accompanying drawings, is a specification, like characters on the drawings representing like parts.

This invention relates to filing and indexing equipment of the class in which the sheets are arranged with their margins in overlapping relationship, and my invention is more particularly concerned with improvements relating to the sheets and their relation with the sheet-holders.

My invention will be best understood by reference to the following description, when taken in connection with the accompanying drawings of one specific embodiment thereof, while its scope will be more particularly pointed out in the appended claims.

In the drawings:

Fig. 1 is a front elevation of a filing and indexing equipment embodying my invention;

Fig. 2 is a sectional view on an enlarged scale on line 2—2 of Fig. 1;

Fig. 3 is a sectional view on an enlarged scale on line 3—3 of Fig. 1; and

Fig. 4 is an elevation of one of the sheets unfolded.

Referring to the drawings, and to the embodiment of my invention which is illustrated therein, I have shown for the purposes of exemplification a filing and indexing equipment comprising a plurality of folded sheets 10 assembled face to face consecutively, and with their folds preferably presenting overlapped margins. Preferably, each sheet is folded along a line A—A, parallel with two opposite marginal portions of the sheet. Preferably the folds are not creased or pressed down absolutely flat, but the leaves are spread apart intermediate the fold and the opposite marginal portions thereof, as well shown in Fig. 2. Thus, the sheets present relatively thick overlapping margins, having capacity for rapid and accurate opening of the file or index at the desired point. This is well illustrated in Fig. 2, wherein I have indicated in dotted

lines a finger pressing down a series of sheets, thereby causing a separation from the adjacent sheets which are not subjected to pressure, the result being that the finger can be introduced at the desired point without the necessity of carefully picking the edge of the sheet with the finger nail.

The folded sheet presents many other important advantages, among them being a greater flexibility and durability as compared with a single card of equal weight. While a card of a given thickness will often

crack, or remain more or less permanently bent when doubled over accidentally, a folded sheet whose total thickness equals that of the card will resist cracking and permanent injury to a very marked degree.

Another consideration which is of importance is the fact that in comparing folded sheets with cards of equal weight, the folded sheets are less expensive in first cost, and since they are more durable, their ultimate

cost is very much less. Still another advantage is that the folded sheet has twice the writing surface of a single sheet, this being available by unfolding and turning the sheet inside out. Moreover, the cut edge of a single sheet is apt to split and become shabby owing to the fact that the cut fibers of the paper are exposed at the edge, whereas in the case of the folded sheet, the fibers are uncut and unbroken, and resist wear to a

much greater degree. Many other advantages will readily suggest themselves to those skilled in the art.

The sheets may be held by any suitable sheet-holders, and the latter may be mounted on any appropriate mounting. In the present example, the two margins of the sheet opposite the line of the fold are provided with any suitable number of perforations 11 (see Fig. 4), and preferably the perforations of one margin register with those of the other when the sheet is folded, as shown in the lower part of Fig. 1, and in section in Fig. 3. These perforations may serve to receive a part or parts of a suitable sheet-holder, and while several varieties may be employed, I have herein shown a plurality of tubular sheet-holders 12, each provided with a sheet-receiving slot 13 extending lengthwise thereof, as shown in Fig. 3. The sheet is suitably locked to the sheet-

holder, as by providing the slot 13 with offsets formed by recesses 14 and corresponding tongues 15, the latter normally extending through the perforations 11, as shown in Fig. 3. Thus the sheet is securely locked against accidental disengagement from the sheet-holder, but may be removed therefrom at will by relative sliding movement lengthwise of the sheet-holder. When this takes place, the tongues 15 ride out of the perforations 11, and permit the sheet to be withdrawn from the holder, as will be readily understood from an examination of Fig. 3. The sheet may be reinserted by the reversal of the foregoing operation. Since the sheets are folded and their leaves are apt to spread apart, this tendency is manifested in an increased tendency of the sheet to fill the slot 10, and to resist accidental movement therein, as will be evident from an inspection of Fig. 2.

While the sheet-holders may be mounted in a wide variety of mountings, I have herein shown a common form of mounting 16, preferably comprising a thin sheet metal back provided with inwardly-projecting flanges 17 forming channels 18 to receive the terminal portions of the sheet-holders 12, the latter being preferably cylindrical, and constituting trunnions about the axes of which the sheets may be turned to and fro to expose either face, while still maintaining the overlapping margins in properly spaced relationship.

Undue movement of the sheet-holders lengthwise of the channels may be prevented by any suitable upper and lower stops, but in the present example, I have shown for this purpose flexible rods 19 provided with enlarged cylindrical terminal portions 20, having reduced ends 21 extending through perforations 22 in the flanges 17. Removal of one of these rods from above or below the sheet-holders allows the latter to be displaced lengthwise of the channels, thus permitting the sheet-holders to be removed, replaced and rearranged at will. Of course, when the sheet holders are in place in the mounting, the removal of the sheets therefore is impossible, because the flanges 17 prevent the sheets from being withdrawn endwise. The removal and replacement of the rod 19 may be readily accomplished by bowing the same to reduce its length, and to withdraw its ends from the perforations in which they are normally seated. The sheets may be arranged in either upstanding or depending fashion, as may be desired, although in the present instance, I have shown them upstanding.

Having thus described one embodiment of my invention, what I claim and desire by Letters Patent to secure is:

1. A file comprising, in combination, a series of folded, paper, record sheets whose

5 folds are presented to view in overlapping relationship, and sheet-supporting means having provision for swiveling to permit said sheets to be swung to present either of two faces to view.

2. A file comprising, in combination, a series of folded, paper, record sheets whose folds are presented to view in overlapping relationship, and a pivotal mounting by which said sheets are carried with their 75 folds presented at the front for inspection and manipulation to present the record on either face to view.

3. A filing equipment comprising in combination, a series of overlapping elements 80 each comprising a sheet folded along a line parallel with two opposite marginal portions, the latter being provided with registering perforations, and a series of sheet holders having portions received in said 85 perforations, respectively.

4. A filing equipment comprising in combination, a series of overlapping elements each comprising a foldable sheet having a folding line parallel with two marginal portions, the latter being provided with perforations, sheet-holding means received in said 90 perforations, and a mounting in which the folds of said sheets are presented at the front for manipulation.

5. A filing and indexing equipment comprising, in combination, a series of overlapping sheets and a plurality of sheet-holders, the overlapping part of each sheet being 100 folded along a line parallel with two opposite marginal portions which are brought together and held by one of said sheet-holders, the folded edges of the sheets being presented at the front for inspection and manipulation.

6. A filing and indexing equipment comprising, in combination, a plurality of sheets and a plurality of sheet-holders, each sheet being folded along a line parallel with two opposite marginal portions which are 110 brought together and held by one of said sheet-holders, the folds of said sheets being held by said sheet-holders in overlapping relationship.

7. A filing and indexing equipment comprising, in combination, a plurality of folded sheets whose folds are arranged in overlapping relationship, each sheet presenting two leaves brought together, and a plurality of sheet-holders, each interlocked with the 120 leaves of one of said sheets.

8. A filing and indexing equipment comprising, in combination, a plurality of folded sheets whose folds are arranged in overlapping relationship, and a plurality of sheet-holders, each having an opening in which the leaves of one of said sheets are received.

9. A filing and indexing equipment comprising, in combination, a plurality of folded sheets whose folds are arranged in overlapping 130

ping relationship, and a plurality of sheet-holders having means extending through both the thicknesses of the respective sheets.

10. A filing and indexing equipment comprising, in combination, a plurality of folded sheets whose folds are arranged in overlapping relationship, and a plurality of sheet-

holders, the leaves of each sheet being provided with registering perforations in which said sheet-holders are received.

In testimony whereof, I have signed my name to this specification.

JOHN T. QUIGLEY.
